UNITED STATES PATENT OFFICE

ARTHUR D. WIGGINS, FREDERICK T. WIGGINS, AND GEORGE M. KNAPP, OF CHICAGO, ILLINOIS, ASSIGNEES TO THE JOHN B. WIGGINS COMPANY, OF CHICAGO, ILLINOIS, A CORPORATION OF ILLINOIS

CARD CASE AND BINDER

Application filed March 16, 1931. Serial No. 523,108.

This invention relates to improvements in card cases and binders and it consists of the matters hereinafter described and more particularly pointed out in the appended claims.

- 5 The card case with which our invention is more particularly concerned, is of the kind including top and bottom covers foldably connected together at one end for an opening and closing movement and to the inside of 10 one of said members is attached means for securely holding a stack of business, personal, calling or like cards that may be detached from the stack as required.
- The primary object of the invention is to 15 provide a device of this kind having a binding means on one end of one cover for enclosing and holding the stub ends of a stack of cards and which means includes a part of a fastening device for detachable locking engagement with an associated part on the end of the other cover.

Another object of the invention is to provide a device of this kind in which the binder includes a card-receiving guide and a clamp 25 plate movable thereon in the direction of the length of the cards and so operatively connected thereto as to clamp upon the card ends with a compressing action to hold or bind them in place with respect to the cover.

30 A further object of the invention is to provide an improved binder for this purpose including but two parts; namely, a card end receiving guide and a clamping plate, the former having certain slots therein to receive parts extending inwardly from the clamping 35 plate whereby the clamping plate is movable on the guide to grip the associated card ends to hold them in place.

The above mentioned objects of the invention, as well as others, together with the many advantages thereof, will more fully appear as we proceed with our specification:—

In the drawings:

Fig. 1 is a perspective view of a card case embodying the preferred form of the invention in its open position, ready for the removal of a card therefrom when so desired.

Fig. 2 is a perspective view of a card case embodying a modified form of the invention 50 and will be more fully referred to later.

Fig. 3 is a view in side elevation of the binder end of the card case shown in Fig. 1 with the top cover member in its detachably locked position with respect to the bottom cover member.

Fig. 4 is a view in side elevation of the end of the bottom cover member with the binder thereon, the clamping plate of which is in a position to permit the entrance of a stack of cards into the associated card-receiving 60 guide.

Fig. 5 is a perspective view of the clamping plate of the binder.

Fig. 6 is a perspective view of the card-receiving guide of the binder.

Fig. 7 is a plan view of one of a number of cards adapted for use in connection with the improved case and binder.

In general our improved card case and binder includes top and bottom covers which 70 are operatively connected together at one end for an opening or closing movement. Preferably such covers are made as end parts of a fairly flexible strip of suitable material formed transversely at the middle to permit the desired folding movement between said covers. At one end of one of the covers is secured a card stub or end receiving guide including a card end edge engaging wall or shoulder having an upright flange at each 75 end. These flanges which are adapted to be engaged by parts of the side edges of the cards are each formed with a peculiarly shaped slot therein.

Associated with said card stub or end receiving guide is a clamping plate including a top wall for active clamping engagement with the topmost card end, and end flanges each with an inturned projection for engagement in an associated slot in each flange of the guide. These slots are of such formation that when the clamping plate is moved in one direction of the length of the cards, the projections so engage in said slots as to exert a clamping action on the card ends which tends to compress them in the guide and to hold them in place therein. Upon a movement of the clamping plate in the other direction, this clamping action is removed 90 from the card ends to permit the removal of 95 100

the stubs and the insertion of a fresh stack of cards in their stead. Movement of the clamping plate in the first direction, then acts to clamp said fresh stack of cards in place.

Referring now in detail to that embodiment of the invention illustrated in the drawings, and especially to the figures, other than Fig. 2, 1 indicates as a whole, a folding card case including top and bottom end cover members 2 and 3 respectively, separated by a more flexible transverse area 4 providing the hinge arrangement whereby said covers may be folded into superposed closed relation and unfolded into open position in the manner well known. Such cases which may be made of many different kinds of materials, are usually in themselves, fairly flexible for ease in carrying them in the pocket of a piece of wearing apparel.

At one end of one cover and preferably at the free or outer end of the bottom cover, we provide a novel arrangement for clamping or otherwise securing the stub ends 5 of stack of cards 6 therein, the cards and stubs being connected along a transverse weakened line 7 for quick and easy detachment of the card from the stub. Such an arrangement or means just above mentioned, comprises a card stub guide 8 and an associated clamping plate 9.

The guide 8 has a base or bottom wall 10, a transverse upright wall 11 forming a shoulder or abutment, and end walls 12-12 each of a height approximating that of the wall 11 and of a length less than that of the base. In each end wall is provided a slot having a part 13 disposed parallel with the base and a second part 14 curved or inclined upwardly therefrom toward the wall 11. When such a guide is positioned in place, its upright wall is arranged adjacent the transverse edge of the bottom cover and this brings the end walls 12 near the top and bottom edges of said cover. "Top" and "bottom" are employed in this instance with reference to the inscriptions upon said card and are used only for convenience. To secure the guide in this position, rivets 15 pass through suitable holes in both the base and said bottom cover.

The clamping plate 9 is adapted to embrace the transverse and end walls of the base and includes a top wall 16 formed at its inner free edge with a downturned lip or tearing edge 16^a. A transverse wall 17 depends from the top wall as do end walls 18-18 and in each end wall is formed an inturned, integral projection 19 to engage in the slots of the associated end walls 12 of the guide 8. On the top wall of the clamping plate is provided the member 20 of a snap fastener, the co-acting member 21 of which is disposed on the inside of the end of the other cover member as best shown in Fig. 1. With the clamping plate mounted on the guide, as described, when it is moved toward the transverse up-

right wall 11 thereof, the projections 19 will ride up the curved portions 14 of the slots in said end walls of the guide and will elevate the clamping plate as a whole and at the same time will cause said plate to overhang 70 the wall 11 of the guide as best shown in Fig. 4.

When the parts are in the position just described, it is possible to insert the stub ends of a stack or plurality of cards into the guide, under the lip or tearing edge of the clamping plate, and to engage the rear wall 11 of the guide. This positions the cards in place in the guide. Thereafter the clamping plate is moved inwardly and the projections thereon will follow down the curved parts 14 of the slots in the end walls of the guide into the straight parts 13 thereof. This will cause the clamping plate to clamp down on the card stubs 5 with a compressing action and due to the natural resistance to compression, said stubs will act to expand so that projections are forcefully engaged with the top edges of the straight parts of said slots. This causes the clamping plate to securely hold the said stubs in the guide so that all cards are bound in place in the case. In this respect, it is pointed out, that the bent-down lip providing the tearing edge of the clamping plate will be disposed substantially in the plane of the weakened lines 7 of the card so that when it is desired to present one of said cards for its intended purpose, said lip serves as an edge along which the card can be torn from the stub, the stubs being retained in the binder. After the card has thus been removed from the case, the top cover 2 is folded down into closed position when the part 21 of the fastening device carried thereby will register and engage with the other part 20 of the fastener on the clamping plate 9 of the binder so that the top cover is removably secured in place.

When the closed and locked card case is being carried in the pocket, or other place, both ends of the cards are protected against soiling.

In Fig. 2, we have illustrated a slightly modified form of the invention, wherein the binder is disposed on that end of the bottom cover near the transverse flexible part 4 of the case, instead of at the outer or free end thereof as before described. In this Fig. 2, like reference numerals indicate like parts as heretofore. When the binder is so arranged on the cover, the clamping plate 9 and top cover 2 are each devoid of any fastening device parts.

A card case and binder made as described has many advantages. It consists of but a few parts which may be readily produced and assembled at an extremely low cost. Such parts are easily manipulated for refilling the case with cards and in one instance the binder may be advantageously employed as a sup-

port for a part of a fastening device to secure the top cover in place.

The binder includes no parts requiring screws or the like that may become either loose or lost so that the device will serve satisfactorily for a long time.

While in describing the invention, we have referred in detail to the form, arrangement and construction of the parts thereof, the same is to be considered merely as illustrative so that we do not wish to be limited thereto except as may be specifically set forth in the appended claims.

We claim as our invention:—

15. 1. A device of the kind described embodying therein a cover, a card end receiving guide member, a clamping member mounted for a relative movement with respect to said guide member, one of which members is secured to the cover, and means providing interengaging parts on said members operable in a relative movement in one direction therebetween in the plane of the length of the cards, imposing a binding action on said card ends in the guide and operable in a relative movement in the opposite direction therebetween in said plane, to release said binding action.

20. 2. A device of the kind described embodying therein a cover, a card end receiving guide member fixed to said cover, a clamping member mounted for a movement on said guide member in either direction in the plane of the length of the cards and means providing interengaging parts on said guide and clamping members operable in a movement of the clamping member in one direction for impressing a binding action on said card ends in the guide and operable in a relative movement in the other direction to release said clamping action.

25. 3. A device of the kind described embodying therein a cover, a card end receiving guide member fixed to said cover and including a wall for engagement by the end edges of the cards and shorter walls parallel with the longitudinal edges of the cards, a clamping member associated with said guide member and including flanges coacting with the shorter walls of said guide members which walls and flanges have coacting slot and engaging projections, operable in a movement of the clamping member in one direction parallel with said shorter walls and flanges to impose a binding action on said card ends.

30. 4. In a device of the kind described, a card end guide embodying therein, a base, an upright wall along one edge of the base and shorter walls along other edges of the base and arranged at a right-angle to said first mentioned wall, a clamping plate including flanges associated with said shorter walls of the base, said shorter walls and flanges having a slot and projection connection, operating in a relative movement between said guide and clamping plate in one direction, parallel with

said shorter walls and flanges to bring the clamping plate closer to the base and operating in a relative movement in the other direction to elevate said clamping plate with respect to said base.

35. 5. In a device of the kind described, a card end guide embodying therein, a base, an upright wall along one edge of the base and shorter walls along other edges of the base and arranged at a right-angle to said first-mentioned wall, said shorter walls each having a slot therein with one part substantially parallel with the base and with another part extending upwardly away therefrom, a clamping plate including flanges associated with said shorter walls and having parts formed to extend into said slots, said slots and projections acting in a relative movement of said clamping plate on the guide in one direction parallel with said shorter walls and flanges to bring the clamping plate closer toward the base and operating in a relative movement in the other direction to elevate said clamping plate with respect to said base.

40. 6. In a device of the kind described, a folding card case including top and bottom cover members, means at one end of one of said cover members for binding a plurality of card ends in place in said case, and coacting devices on said means and other cover member for detachably securing said other cover member in a closed position.

45. 7. In a device of the kind described, a folding card case including top and bottom cover members, means at one end of one of said cover members for binding a plurality of card ends in place in said case, and including a movable clamping plate and coacting devices on said clamping plate and other cover member for detachably securing said other cover member in a closed position.

50. 8. In a device of the kind described, a card case comprising top and bottom cover members having a folding connection at one end, means at the other end of one cover member for binding a plurality of cards in said case and coacting devices on said means and on the other end of the other cover member for detachably securing said other cover member in a closed position.

55. 9. In a device of the kind described, a card case comprising top and bottom cover members having a folding connection at one end, means at the other end of one cover member for binding a plurality of cards in said case and including a movable clamping plate and coacting devices on said clamping plates and on the other end of the other cover member for detachably securing said other cover member in a closed position.

60. 10. A device of the kind described embodying therein a cover, means on the cover for positioning a stack of cards thereon, a clamp member mounted for a shifting movement longitudinally of the cover and means for

guiding the clamp member downwardly in said shifting movement for binding the cards in place upon the cover.

11. A device of the kind described embodying therein a cover, means on the cover for positioning a stack of cards thereon, a clamp member mounted for a shifting movement longitudinally of the cover and means for guiding the clamp member downwardly in said shifting movement for binding the cards in place upon the cover, said means being so formed as to retain the clamp member in the limit of its downward movement at one end of said shifting movement.

15. In testimony whereof, I have hereunto set my hand, this 9th day of March, 1931.

ARTHUR D. WIGGINS.

In testimony whereof, I have hereunto set my hand, this 9th day of March, 1931.

20. FREDERICK T. WIGGINS.

In testimony whereof, I have hereunto set my hand, this 9th day of March, 1931.

GEORGE M. KNAPP.
